CLAIM

The ornamental design for a cup game assembly, as shown and described.

DESCRIPTION

FIG. 1 is a perspective view of a cup game assembly showing my new design;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof; and,

FIG. 7 is a left side elevational thereof.

The portions shown in broken lines, indicia and surface lines are for environment and illustrative purposes only, forming no part of the claimed design.
